CLAIM

The ornamental design for a casing for machines, as shown and described.

DESCRIPTION

FIG. 1 is a left front perspective view of the casing for machines design;

FIG. 2 is a right rear perspective view of the design of FIG. 1;

FIG. 3 is a left side view of the design of FIG. 1;

FIG. 4 is a front end view of the design of FIG. 1;

FIG. 5 is a rear end view of the design of FIG. 1;

FIG. 6 is a right side view of the design of FIG. 1; and,

FIG. 7 is a top view of the design of FIG. 1.

The broken lines depict portions of the casing for machines and form no part of the claimed design.
